UNITED STATES PATENT OFFICE

WILLIAM MODRA, OF ST. LOUIS, MISSOURI

CAP FOR FIRE-PLUGS

Application filed December 19, 1930. Serial No. 503,444.

My invention has relation to improvements in caps for fire-plugs, or similar hydrants, and it consists in the novel features of construction more fully set forth in the specification and pointed out in the claims.

The invention is more particularly directed to a cap embodying a locking mechanism that when set to locking position, prevents the removal of the cap until the lock thereof is first released, so that the cap may not be removed by street urchins and other meddlers.

The present device is an improvement over my copending applications Serial Nos. 494,649 and 500,833, filed November 10, 1930 and December 8, 1930 respectively, in that the cap is made in sections, each being permanently secured to the plug, and that the locking mechanism is greatly simplified so as to reduce the cost of construction.

The principal object of the invention is therefore the provision of a cap permanently fixed to the plug and readily movable to uncover the threaded nozzle thereof for connection with the hose leading to the pumping engine. It is a further object to provide the articulating cap sections with a suitable lock operable only by the application of a special wrench or key to guard it against tampering. It is also the object to provide a fire-plug cap having the properties mentioned that is positive in its action, simple in its construction, and that may be manufactured at a comparative low cost.

Further and other advantages will be better apparent from a detailed description of the invention in connection with the accompanying drawings in which:

Figure 1 is a front elevation of a fire-plug equipped with my improved nozzle cap; Fig. 2 is a side elevation thereof; Fig. 3 is a cross-sectional detail taken on the line 3-3 of Fig. 1 with part of the plug broken away; Fig. 4 is an enlarged cross-sectional detail taken on the line 4-4 of Fig. 1 with part of the plug broken away; Fig. 5 is a vertical cross-sectional detail taken through the plug nozzle on the line 5-5 of Fig. 2; Fig. 6 is a cross-sectional detail taken on the line 6-6 of Fig. 4; Fig. 7 is an enlarged front elevation of the middle portion of the plug showing the nozzle

covered by one cap section, the other cap section having been opened; Fig. 8 is a sectional view similar to Fig. 5 showing a modified form of retaining lugs for the locking bolt; Fig. 9 is a cross-sectional detail taken on the line 9-9 of Fig. 8; Fig. 10 is a side elevation of that portion of the plug carrying the nozzle showing a band clamped thereon whereby my improved cap is applicable to old plugs now in use; Fig. 11 is a front elevation of said band; and Fig. 12 is a section similar to Fig. 5 showing a modified form of locking bolt.

Referring to the drawings P represents a fire-plug of conventional design having its outlet nozzle, or spout S covered by my improved closure cap comprising semi-circular articulating sections 1, 1'. The function of the cap sections is to encase the threaded flange t of the nozzle S and protect the threads thereof against injury so that no difficulty may be encountered when it is necessary to attach the hose of the pumping engine to said threaded flange. The sections 1, 1' are similar in shape and are respectively hinged to oppositely disposed lugs 2, 2' by means of hinge brackets 3, 3'. The section 1 has a boss 4 projecting from it in which there is an axially disposed opening 5 to serve as a bearing for a shaft 6 having a tapering polygonal head 7 at its outer end, and a reduced polygonal extremity 8 at its inner end, the extremity 8 carrying a cross bar, or latch, 9 held against the shoulder 10 at the base of the extremity 8 by means of a coiled spring 11 confined between said cross bar and a washer 12 screwed into the end of the extremity 8 by means of a cap screw 13. In order to insure the proper articulation of the cap sections 1 and 1', the edge 14 of section 1 is provided with triangular lugs 15, 15 which are adapted to enter correspondingly shaped recesses 16, 16 in the edge 17 of cap section 1'. The edge 17 of section 1' has a notch 18 at the center to accommodate the shaft 6 and is slightly recessed as shown at 19, 19 to provide clearance for the latch 9 when the sections 1, 1' are brought into articulating relation to close the cap. On the inner surfaces 20, 20' of sections 1, 1' detents 100

21, 21 and 22, 22 are provided for the latch 9, said detents 21, 21 and 22, 22 being arcuate in shape and spaced apart as shown at s , s' , and inclined upwardly toward the respective 5 spaces so as to provide abutments for the ends of the latch 9 and hold said latch firmly in its locking position, which is transversely of the articulating edges of sections 1, 1'. This is clearly shown in Figs. 5 and 6. The 10 tension of the spring 11 is such that it is impossible to dislodge the latch 9 from confinement of the detents 21, 21 and 22, 22, except by the application of a specially shaped wrench, or key, to the polygonal head 7. As 15 shown in Fig. 3, an overlapping flange f is provided on section 1 for effecting a more secure engagement of the sections and better closure.

In Figs. 8 and 9 I show a modified form of 20 detent for holding the latch 9. Instead of the inclined arcuate detent of the main form, I may employ a pair of conical knobs 23, 23 on section 1 and 23', 23' on section 1'.

In applying my improved cap to old fire- 25 plugs now in use which are not equipped with lugs 2, 2', I employ a band 24 disposed around the nozzle S of the plug, said band being shaped to follow the intersecting line 25 of the nozzle with the plug, and having 30 hinge lugs 26 riveted to it at oppositely disposed points. The opening 27 between the ends of the band is held in closed position by means of a bolt 28 traversing flanges 29, 29 on the ends of the bands, and a nut 30 screwed 35 over said bolt. In some cases the spout S may taper slightly so that the band 24 would not remain permanently in place on the spout. When this condition is encountered, I provide a band that will entirely envelop the 40 body of the fire-plug.

In Fig. 12 I show a modification of the locking mechanism for the cap sections which comprises a pair of keepers 31, 31 disposed on opposite sides of the stem 8'. Latches 32 45 fixed on the ends of stems 33, 33 are adapted to enter the keepers 31, 31 and the stems 33, 33 project from a cross-member 34, which is adapted to be engaged by a cam 35 mounted on the stem 8'. Springs 36 are disposed on 50 the stems 33 to urge the latches 32 out of their housings 37, 37. When a wrench is applied to the polygonal extremity 7 and the extremity 8' rotated thereby, the cam 35 will engage the bar 34 and force the latches 32 out 55 of the keepers 31 so that the cap sections 1, 1' may be opened. On removing the pressure of the wrench, the springs 36 will force the latches 32 outwardly so that they will be in 60 position to snap into the keepers 31, 31 when the caps 1, 1' are brought together.

Having described my invention I claim:

1. In combination with a hydrant having a discharge nozzle, a closure cap for said nozzle, said cap comprising sections hinged to 65 the nozzle in opposed relation and adapted

to be moved into articulating relation to enclose the nozzle, and means within the sections for locking them together, said locking means comprising a latch rotatably mounted in one of the sections and suitable detents for engaging said latch. 70

2. In combination with a hydrant having a discharge nozzle, a closure cap for said nozzle, said cap comprising sections hinged to the nozzle in opposed relation and adapted to be moved into articulating relation to enclose the nozzle, means within the sections for locking them together, said locking means comprising a latch rotatably mounted in one of the sections and suitable detents for engaging said latch, and key operated means associated with the latch for actuating said latch. 75

In testimony whereof I hereunto affix my signature.

WILLIAM MODRA.
